SIGN

Raymond L. Marten, St. Louis, Mo.

Application February 27, 1937, Serial No. 128,111

7 Claims. (Cl. 40—142)

This invention relates generally to display apparatus, and more particularly to an improved sign or attraction board especially applicable for use in connection with theatres for advertising feature presentations which are periodically changed.

An object of my invention is to provide an improved sign of the character described which furnishes a highly attractive display of advertising or other informative media when illuminated by natural light during the day, or electrically, by luminous discharge tubes at night.

Another object of my invention is to provide a sign of this character which is designed and constructed to permit the letters or other indicia to be readily removed and replaced when it is desired to change the display.

The sign or display device embodying the invention, essentially comprises a louvered background structure constituted by a series of parallel, inclined plates. The plates, disposed one above another in spaced relation, are adapted to reflect day-light, or light from luminous discharge tubes mounted between the plates, toward an observer. Opaque sign characters, mounted immediately forwardly of the background structure in a novel manner so as to be easily removed or interchanged, appear in silhouette against the highly illuminated and contrasting background. The reflecting plates tend to reduce the glare normally accompanying direct illumination by discharge tubes and provide a brilliant, yet softly lighted background for the display characters which does not discomfort the observer.

Signs of the character described as heretofore designed and constructed have certain disadvantages, overcome by the present invention, which detract from the general usefulness and attractiveness thereof. For example, in the signs of former construction the angular arrangement of the reflector plates is such as to provide little or no protection to the luminous discharge tubes, the tubes being readily susceptible of injury as by hail and sleet. When such signs are mounted overhead, as on a theatre canopy over a side-walk, a highly desirable location for the signs, light from the sun gives a dull or grayish cast to the plates which detracts from the effectiveness of the sign, since the contrast between the background and sign characters is not pronounced. Moreover, when such signs are illuminated by the discharge tubes, all of the light rays are deflected upwardly or intercepted by the reflector plates, being lost for any useful purpose

except to illuminate the sign background structure, whereas with my improved sign construction light directly from the tubes serves to illuminate the side-walk or the like immediately below the sign, this being very desirable where the sign is used in connection with theatres.

Another disadvantageous feature inherent in former signs of louvered type is that the louvers tend to collect dirt, ice and rain water which impair their light-reflecting quality. In my improved sign the louvers are arranged to shed all ice, moisture and foreign matter.

A further object of my invention is to increase the range of "readability" of an overhead sign of the character described, or to provide a sign of this type which can be easily read by an observer at a distance from the sign or directly below the same.

These and other objects and advantages will appear from the following detailed description setting forth a preferred embodiment of my invention, and from the accompanying drawing in which:

Fig. 1 is a perspective view of my improved sign.

Fig. 2 is a sectional, elevational view of the sign illustrated in Fig. 1.

Fig. 3 is a sectional plan view taken at line 3—3 of Fig. 2.

Fig. 4 is a side elevational view showing a sign of modified form with a part of the sign wall broken away to illustrate more clearly the construction.

Referring now by character of reference to the drawing, my improved sign includes a sheet metal housing structure comprising horizontal top and bottom walls 5 and 6 respectively, vertical rear wall 7, and end walls 8 having inclined forward margins 9, the top, bottom and end walls defining the forward, substantially open face of the housing structure. The plane of the open front face is inclined, sloping downwardly toward the vertical rear wall 7. Inturned flanges 10 and 11 at the front margins of the top and end walls respectively border the face of the housing structure and give the same a finished, trim appearance.

Spaced inwardly from the open front face of the housing is a panel 12 on which the reflector plates 14, hereinafter described, are mounted. The panel 12 may be of stepped surface configuration as appears from Fig. 2, the riser portions 13 receding progressively from the top to the bottom of such panel, or the panel may be substantially planar and inclined, to parallel the

plane of the inclined front face of the housing, as appears from Fig. 4.

5 Mounted on the forward surface of panel 12 are the reflectors 14, each thereof comprising an elongated plate which extends horizontally across the front opening of the sign. The plates 14 are disposed in parallel, uniformly spaced relation and where the stepped mounting panel 12 of Fig. 2 is employed, each plate is associated with and secured to one of the riser portions 13 of the panel. The reflector plates 14 are secured as by rivets 15 along their upper horizontal margins to the panel 12, and slope downwardly and forwardly away from their upper, secured margins 10 as appears from Figs. 2 and 4. The lower horizontal edges 16 of the reflector plates 14 lie approximately in the inclined plane of the front face of the sign, or in an inclined plane which is parallel to, and spaced a small distance inwardly 15 from the front face of the sign. The front face 17 of panel 12, and both front and rear faces 18 and 19, respectively, of the plates 14 are provided with suitable light-reflecting surfaces, preferably by coating these surfaces with layers of white vitreous enamel.

15 The removable and interchangeable letters or sign characters 20 are formed of sheet metal, fibrous or composition material, and have a surface coating of black paint to enhance their contrast with the white background by day, and with the highly illuminated colored background by night. The character elements 20 are provided, near their upper rear edges, with hook-like brackets 21 which are adapted to engage any of the inwardly turned flanges 22 at the lower extremities of the reflector plates 14, or an inwardly turned flange 23 at the lower extremity of the horizontal trim portion 10. The mounting flanges 22 and 23 are preferably turned angularly 20 upwardly and rearwardly as shown in Fig. 2.

Near the lower inner margin of each character element is provided a mounting hook 24 which is adapted to engage any one of a series of cords or wires 25. The wires 25 are secured at opposite 25 ends to the end walls 8 of the housing, and stretch horizontally in the space between each pair of adjacent reflector plates. One or more springs 26 or other suitable tensioning means are provided for each of the wires 25, which tensioning means 30 may be located so as to be substantially concealed by the side trim flanges 11. It will now appear that the character elements may be readily and quickly attached to the sign structure by causing their mounting hooks 21 to engage and seat over the flanges 22, and their lower hooks 24 to engage the appropriate wire 25. The tensioned wire serves to draw the lower ends of the characters inwardly against the lower extremity of an adjacent reflector plate, securing the character in 35 an angular, slightly downwardly facing position as shown.

The sign is adapted to be illuminated at night by lighting tubes, preferably of the luminous discharge or neon gas variety. One or more of the 40 said tubes are provided for lighting each reflector plate. The tubes extend horizontally across the face of the sign and are preferably located in the space between the upper margin of one reflector plate and the lower margin of the next higher 45 reflector plate. In the present example a pair of lighting tubes 27 and 28, are associated with each reflector plate and both tubes are shielded from natural elements, such as snow, hail and water, by the overhanging reflector plate 18, the upper- 50 most pair of tubes being protected by the trim 10.

The tube 27 may be filled with neon gas to produce the characteristic red colored light, and tube 28 may be filled with argon to produce blue colored light. The tubes 27 and 28 are supported in any suitable manner from the panel 13 or 5 plates 18 by means of conventional insulating mounting brackets, not shown, and the tubes are connected electrically in any suitable manner to a transformer 29, mounted in the enclosure between panel 13 and rear wall 7. A suitable switch 10 or motor-driven commutator may be employed in the electric circuit for causing joint or independent energization of the tubes 27 and 28 whereby to obtain a variety of changing color 15 effects.

It may be noted that when the sign thus described is mounted overhead, a part of the light from the tubes is transmitted downwardly without interruption or reflection by the plates 13 and provides direct illumination for the ground 20 area below the sign. Thus the tubes are revealed to an observer within a certain limited distance from the sign, and the combination of direct and reflected illumination, in such instances, enhances the attractiveness of the sign. Where 25 both red and blue light-producing tubes are provided, as in the present example, the red tube is preferably positioned outwardly of the blue tube, or in such position as to be more concealed by plates 13 and their flanges 22, from direct view 30 by an observer. The softer, glare-free light from the blue tube 28, when viewed directly does not discomfort the eyes of an observer.

When illuminated by the tubes 27 and 28 the characters are silhouetted against the colored, 35 highly illuminated background having the appearance of horizontal bands of light which merge, one into another, and produce a highly pleasing effect. The color of the individual light bands may be varied and numerous color combinations obtained, increasing further the effectiveness of the sign.

The forward reflecting surfaces 18 of the plates 14 face angularly upwardly, and accordingly are in an ideal angular position to catch and reflect 45 light from the sky or sun. Thus, during the day the louvered structure provides a white, highly lighted back-ground which contrasts markedly with the black characters, which do not so readily reflect the light because of the described nature of their color, surface, and angular position. 50

I have described and illustrated my invention as embodied in signs having both stepped and inclined planar panel members 12, and means of presently preferred type for detachably securing 55 the sign characters to the background structure, and other preferred constructional features. However, it is to be understood that the invention is not limited to the particular means herein shown and described, as various changes may be 60 made without departing from the spirit and full intendment of the invention as defined by the following claims.

I claim as my invention:

1. A sign comprising a substantially upright 65 member, a series of horizontally elongated reflector plates secured, one above another, at the upper edges thereof, to said member, said plates being inclined downwardly toward their lower edges which are spaced forwardly of said member, the lower edges of said plates being disposed in an inclined plane sloping downwardly and rearwardly, rearwardly directed flanges formed on said plates adjacent the lower edges thereof, sign characters, and means detachably connect- 75

ing the characters to said flanges with the characters disposed in the sloping plane defined by the lower edges of said plates.

2. A sign comprising a substantially upright panel of inclined trend having a light-reflecting forward surface, the inclination of said panel being downwardly and rearwardly from its upper edge, a series of horizontally elongated reflector plates secured in spaced relation, one above another, to the forward surface of said panel, said reflector plates being inclined downwardly and forwardly away from said panel; luminous discharge tubes extending horizontally between the reflector plates, and opaque sign characters detachably mounted adjacent the forward edges of said reflector plates.

3. A sign comprising a substantially upright panel of inclined trend having a light-reflecting forward surface, the inclination of said panel being downwardly and rearwardly from its upper edge, a series of horizontally elongated reflector plates secured in parallel, spaced relation, one above another, to the forward surface of said panel, said reflector plates sloping downwardly and forwardly away from said panel and having their forward edges disposed in an inclined plane corresponding to the trend of said panel; illuminating means disposed between the reflector plates, and sign characters detachably mounted on the reflector plates substantially in the plane of the forward edges thereof.

4. A sign of the character described comprising a substantially upright panel having vertical, stepped surfaces receding downwardly from the upper, forward margin of the panel, a series of horizontally elongated reflector plates, each thereof being secured along its upper edge to the upper edge of one of said panel surfaces, said plates being inclined downwardly and forwardly from its secured edge; horizontally extending luminous discharge tubes disposed between adjacent reflector plates, and sign characters detachably secured to the forward edges of said reflector plates.

45 5. A sign of the character described including a substantially rectangular housing structure having an open front face, a series of elongated, horizontally extending reflector plates mounted in parallel spaced relation, one above another, 50 within said housing structure, said reflector plates being inclined downwardly toward the front face of the housing structure and having their forward margins disposed substantially in the plane thereof; luminous discharge tubes extending horizontally within said housing struc-

ture, each of said tubes being mounted between the upper and lower marginal portions of relatively adjacent reflector plates, inwardly turned flanges formed on the lower, forward edges of said reflector plates, substantially flat, opaque 5 sign characters, and hook-like elements projecting from the rear faces of said sign characters adapted for detachable engagement with said reflector plate flanges.

6. A sign of the character described comprising 10 a substantially rectangular housing structure having an open front face, a series of elongated, horizontally extending reflector plates, mounted one above another in parallel, spaced relation within said housing structure, said reflector 15 plates being inclined downwardly toward the front face of the housing structure and having their forward margins disposed substantially in the plane thereof; luminous discharge tubes extending horizontally between said reflector plates, 20 substantially flat, opaque sign characters, and means for detachably mounting said sign characters adjacent the forward margins of the reflector plates, said means including hook-like 25 members projecting from the rear face of said sign characters, and flexible, spring tensioned elements extending horizontally along the reflector plates, adapted for releasable engagement by said members on the sign characters.

7. A sign of the character described comprising 30 a substantially rectangular casing having an open front face, an inclined panel disposed within said housing structure facing the open front face thereof, said panel sloping downwardly and rearwardly, a series of elongated horizontally extending reflector plates disposed, one above another, between said panel and the front face of said housing structure, said reflector plates being inclined downwardly toward the front face of the housing structure, the forward margins of said 35 plates being disposed in an inclined plane substantially parallel with the plane of said panel, and having inwardly turned flanges thereon; luminous discharge tubes extending horizontally 40 within said housing structure between upper and lower marginal portions of adjacent reflector plates, flexible, spring-tensioned members extending along said reflector plates, and flat, opaque sign character elements each having vertically spaced mounting brackets projecting from 45 the rear faces thereof adapted detachably to engage a reflector plate flange and a spring-tensioned member.

RAYMOND L. MARTEN. 55
